UNITED STATES PATENT OFFICE.

HENRY P. ROBERTS, OF BOSTON, MASSACHUSETTS, ASSIGNOR TO GEORGE O. RUSSELL, OF LEXINGTON, AND NELSON W. SANBORN, OF MALDEN, MASSACHUSETTS.

BRACKET FOR ROLLER-CURTAINS AND CURTAIN-RODS.

SPECIFICATION forming part of Letters Patent No. 631,674, dated August 22, 1899.

Application filed November 19, 1898. Serial No. 696,869. (No model.)

To all whom it may concern:

Be it known that I, HENRY P. ROBERTS, of Boston, county of Suffolk, State of Massachusetts, have made certain new and useful Improvements in Brackets for Roller-Curtains and Curtain-Rods, of which the following is a description sufficiently full, clear, and exact to enable any person skilled in the art or science to which said invention appertains to make and use the same, reference being had to the accompanying drawings, forming a part of this specification, in which—

Figure 1 is a front elevation of a window, showing a roller-curtain and a curtain-rod supported in position by my improved bracket; Fig. 2, a perspective view, enlarged, of the bracket detached; Fig. 3, a vertical section on line 3 3 in Fig. 2, illustrating details; Fig. 4, a view showing a modification in the bracket; and Fig. 5 a view like that in Fig. 1, showing a use of the bracket in ventilation.

Like letters of reference indicate corresponding parts in the different figures of the drawings.

My invention relates especially to a device for frictionally supporting roller-curtains and curtain-poles in the casings of windows, whereby it becomes unnecessary to scar the wood-work by the screws and brads ordinarily used in fixtures of this class.

The nature and operation of the device will be readily understood by those conversant with such matters from the following explanation.

In the drawings, A represents a window-casing, and B a spring-actuated shade or curtain roller of ordinary construction.

D represents a curtain-pole, and C the bracket considered as a whole.

The bracket C comprises an approximately semi-elliptical metal spring f, to the inner faces of the ends of which cups g are respectively secured by screws or rivets d. These cups hold plugs h of friction-cloth or corrugated rubber or any suitable material that will impart sufficient frictional hold on the walls of the casing A when the springs f are expanded. Centrally on the apex of the spring there is fast a socket k, fitted to receive the end of a pole D. Through this socket a screw m (see Fig. 3) is turned. This screw is designed to be turned in or out, the end of

the pole D to act as a take-up or adjust said pole relative to said socket. For use with the shade-roller B the spring f is provided with a squared opening p (see Fig. 4) to receive the end of the ordinary spring-winding spindle that projects from said roll. In use the pole D or roller B is adjusted with the brackets at its ends. The length of the spring-curves added to the length of the poles is somewhat greater than the interior breadth of the casing A. The friction-faces h of one spring are engaged with the facing of the casing in desired position. Then said spring is expanded by pressing the pole longitudinally, and the bracket at the opposite end of the pole is sprung into position, as shown. The tension of the springs driving their friction-faces against the woodwork holds the device firmly in position in a manner that will be understood without a more explicit description.

The pole D is designed to support draperies T, and the roller B is for the ordinary shade-roll. Both these forms may be adjusted readily in any position in the casing.

In Fig. 5 the roller B is shown as arranged at a material distance from the cap of the casing, so that the window v may be lowered at the top, as at x, for purposes of ventilation, and yet admit of the shade being used for screening the balance of said window.

Having thus described my invention, what I claim is—

1. As a new article of manufacture the bracket, C, comprising spring, f, provided with the cups, g, containing friction-plugs, h; and the socket, k, at the apex of said spring.

2. The bracket, C, comprising the spring, f, provided with friction-faces in combination with the socket, k, and the adjusting-screw, m, all being arranged substantially as specified.

3. As a new article of manufacture the bracket, C, comprising the semi-elliptical spring provided with friction-plugs, h, at its ends and an opening in its apex for receiving and retaining a bearing end of a shade-roller substantially as described.

HENRY P. ROBERTS.
